Application December 28, 1935, Serial No. 56,495
Renewed May 5, 1939

26 Claims. (Cl. 178—17)

The invention relates to printing telegraph apparatus, and more particularly to automatic transmitters for the transmission of intelligence telegraphically.

5 Objects of the invention are to simplify materially the construction of telegraph transmitters and to increase the efficiency of their operation.

Another object of the invention is the provision of a transmitter which enables the operation 10 of the associated keyboard at a speed not related to the speed of operation of the telegraph circuit over which the signal impulses are to be transmitted.

15 The above and other objects of the invention are achieved by the provision of a keyboard perforator for preparing a control strip, specifically, a perforated tape, and a tape reader which senses the control indicia or perforations on the prepared strip and which controls the character of 20 the signal impulses transmitted to a connected signaling circuit. Specifically, the tape reader has a pivoted frame carrying the operated elements which include a tape sensing head through 25 which the control tape is advanced step by step by the action of an electromagnet energized intermittently from a signal distributor and a plurality of perforation sensing rods which control, in accordance with the tape perforations, electrical contacts connected to the segments of the 30 signal distributor. Electrical signals thus will be transmitted to a connected circuit, depending upon the position of the electrical contacts, through the action of the distributor. An electromagnet also carried by the pivoted frame 35 withdraws the rods from cooperation with the tape to allow the advancement of the tape by the electromagnet through a tape feeding mechanism provided for that purpose to present the next transverse row of perforations in alignment with 40 the sensing rods.

The perforator supplies tape to the record reader, which operates to transmit signal impulses corresponding to the perforations in the tape through a normally stopped distributor. 45 Upon the initial operation of the perforator, which has the usual tape feed mechanism operated to advance the tape for each actuation of the punch hammer, the tape moves the sensing head from its engagement with the die block of the perforator, and thus opens a pair of contacts included in the energizing circuit of the stop electromagnet of the distributor, which is deenergized to allow the rotation of the distributor and thus the transmission of signal impulses corresponding to the row of perforations in the tape. 55

If the tape is perforated at a rate higher than the rate at which signal impulses are transmitted by the distributor, the tape ejected from the perforator, aided by a coiled spring, will cause the frame carrying the sensing head to rotate about its pivot until it engages a fixed stop. Continued operation of the perforator at the higher speed results in the preparation of additional tape forming a loop between the sensing head of the record reader and the point of perforation, or the die block. However, should there be a cessation 5 in the preparation of the tape or the rate of preparation of the tape be diminished, signal impulses will continue to be transmitted in accordance with the perforations in the tape, and when 10 the loop of tape is exhausted, the sensing head will move step by step by the action of the tape feeding mechanism of the record reader toward the point of perforation until the last row of perforations has been sensed, when the advancement 15 of the sensing head will be arrested, and the operating circuit of the stop electromagnet of the distributor closed and the distributor stopped on the completion of its then cycle of rotation. The distributor will remain stopped until the perforator is again operated, when the distributor 20 will start automatically for the transmission of signal impulses. 25

A better understanding of the invention may 30 be had from the following description, taken in conjunction with the accompanying drawings, wherein,

Fig. 1 is a plan view of the record reader and a fragmentary part of the keyboard perforator; 35

Fig. 2 is a vertical sectional view taken on the line 2—2 of Fig. 1;

Fig. 3 is a vertical sectional view taken on the line 3—3 of Fig. 1;

Fig. 4 shows the circuit connections of the record reader and the transmitting distributor; 40

Fig. 5 is a plan view similar to Fig. 1 but showing the record reader in its advanced position, which will result when the tape is prepared at a rate higher than the speed of transmitting impulses to a connected signaling circuit; and, 45

Fig. 6 shows a section of the perforated tape.

Referring now to the drawings, wherein like reference characters indicate similar parts throughout the several views of the apparatus, and particularly to Fig. 1, the apparatus involved in the practice of the invention comprises two units; namely, a keyboard perforator 10 and a record or tape reader 11. The keyboard perforator 10 is of the construction fully disclosed in Patent 1,182,179 to C. L. and H. L. Krum dated 50 55

May 9, 1916. Of course, other well-known keyboard perforators are equally adaptable for operation in conjunction with the record reader 11. For a full and complete understanding of the 5 operation of the keyboard perforator disclosed, reference should be had to the foregoing patent, for the drawings referred to herein show only as much of the perforator as is considered necessary for a full and complete understanding of the 10 present invention.

The several parts of the apparatus are mounted 15 on a cast-metal base 12 having a depressed front portion 13. Above the depressed front portion, the base is provided with an opening through which the forward ends of a series of keylevers 14 extend. At the rear ends, the keylevers, as disclosed in the foregoing patent, are fulcrumed upon a rod suitably supported in the base 12. The forward ends of the keylevers 14 carry finger 20 keys 15.

The keylevers 14 cooperate with a series of permutation bars, and function to set such bars in various combinations in accordance with a pre-arranged plan; that is, the permutation bars 25 will be set in varying combinations upon the depression of each of the keylevers.

The permutation bars operated through the depression of the keylevers control the setting in corresponding permuted relation of a series of 30 bell crank levers 16. Consequently, for each permuted setting of the permutation bars in response to the operation of keylevers 14, bell crank levers 16 will be correspondingly operated. Extending laterally from one arm of each of the bell crank 35 levers 16 is a punch controlling bar or interponent 17. In the case of a perforator for the preparation of a tape operating on a five-unit code system, five punch controlling bars 17 will be provided and will, as disclosed in Fig. 1, be 40 supported and guided in an oscillating punch actuator 18.

Punch actuator 18 is arranged to be operated 45 through punch hammer 20 in response to the energization of an electromagnet, which is energized in timed relation with the operation of the keylevers 14 and is effective to actuate simultaneously a feed hole punch 19 and a plurality of code punches 21. Feed hole punch 19 is guided in openings formed in hardened steel plates 22 and 50 23 carried by a bracket 24 secured to a plate 25 which in turn is fastened to base 12. The feed hole punch 19, in accordance with well-known and established practice, is held in its retracted position by means of a spring and cooperates 55 with a die block 26 fastened to a guide plate 27 to perforate the feed hole in a tape 28. The opposing sides of die block 26 and guide plate 27 are recessed to form a guide-way for the tape 28.

The end of each interponent 17 opposite the 60 end connected to the bell crank levers 16 is supported by a bar 29 fixed to the under side of the punch actuator 18, and will be moved into or out of alignment with one end of its associated bell crank lever 33 in accordance with the position of 65 the connected bell crank lever 16. For example, with an interponent in its retracted position, the free end thereof will be out of alignment with its associated bell crank lever 33. However, with the interponent in its other position, its free end will 70 be in alignment with the end of its individual bell crank lever 33. There being five interponents 17, five bell crank levers 33 are also provided. The bell crank levers 33 are pivoted on a bracket secured to plate 25, and function to operate code 75 punches 21 which cooperate with a die block 35 to

perforate the tape 28 in accordance with the permuted setting of the interponents 17. As was described in connection with the perforation of the feed hole, the die block 35 and the plate to which it is attached are recessed to provide a 5 guide-way for the tape 28.

Each of the punches 21 has an enlarged portion 36 which is engaged by an arm of a bell crank lever 37, the other arm of which is attached to one end of a spring 38 which has its 10 other end secured to a spring post 39 formed in plate 25. There is a bell crank lever 37 individual to each code punch 21, and each is provided with a bifurcated portion which cooperates with the enlarged portion 36 on the code punches 15 21.

For each operation of punch actuator 18 in response to the operation of punch hammer 20, which will occur upon the energization of the punch magnet (not shown), feed hole punch 19 20 will be operated to punch the feed hole in tape 28 and the bell crank levers 33 will be rotated about their pivot depending upon whether an interponent 17 is in alignment therewith. In the case of those interponents which are aligned with the 25 associated bell crank 33, the code punches 21 individual thereto will be operated to punch the tape 28 in accordance with the permuted setting of interponents 17 in response to the actuation of the particular keylever. The movement of 30 punch actuator 18 and the operation of punches 21 as described causes bell crank lever 37 to rotate about its pivot and extend spring 38. Upon the deenergization of the punch electromagnet through the instrumentality of which punch actuator 18 was operated, the energy of spring 38 will become effective and withdraw the actuated code punches 21 from the tape 28.

Through the operation of feed hole punch 19 and code punches 21, transverse rows of perforations 40 are punched in the tape 28 to represent the different characters or signals such as exemplified in the sample of tape 28 shown in Fig. 6.

Located between the feed hole punch 19 and the code punches 21 is a drum 40 which has on 45 its periphery a series of pins which cooperate with the feed holes punched by feed hole punch 19 to advance tape 28 to present an unperforated area in alignment with the code punches 21. Drum 40 is secured to a shaft supported by a bracket 50 carried by plate 25, and has formed in its lower end a series of ratchet teeth. Cooperating with such ratchet teeth is a holding and a stepping pawl. The stepping pawl is secured to the punch actuator 18, and is advanced to engage the next 55 tooth on the ratchet wheel formed in drum 40 when punch actuator 18 is moved in the direction of the arrow indicated in Fig. 1. When punch actuator 18 is retracted, resulting upon the de-energization of the electromagnet which caused 60 its operation, the stepping pawl causes the rotation of drum 40 a distance corresponding to one tooth of the ratchet wheel and thus effects the advancement of tape 28 a corresponding distance. Cooperating with the pins secured in the 65 periphery of drum 40 is a spring-pressed guide member 41 which holds tape 28 firmly against the periphery of drum 40 and thus facilitates the advancement of tape 28.

Back stepping of tape 28 to correct a row of 70 perforations may be accomplished through the operation of a back stepping device controlled by pivoted lever 42. The back spacing device is fully and completely described in the cited patent, and therefore further description here is be- 75

lieved to be unnecessary, particularly since such device does not form a part of the present invention.

Cooperating with the keyboard perforator 10 is the tape or record reader 11, which includes a supporting plate 45 secured to the side wall of base 12 of the keyboard perforator 10 in a position to bring the sensing head of the record reader in close proximity to the code punches 21. According to the preferred form of the invention, the plate 45 is secured to the base 12 to bring the sensing head 46 of the record reader 11 sufficiently close to the code punches 21 that the last row of perforations inserted in tape 28 may be sensed by the record reader 11.

The record reader 11 also includes a channel-shaped plate 47 provided at one end with a depending post 48 adapted to be inserted in a bushing 49 formed in the supporting plate 45 and engaged by one end of a spring 50, the other end of which is fixed to plate 45. Spring 50 is tensioned in a manner to assist the movement of channel-shaped member 47 and the sensing head 46 away from the tape exit of the keyboard perforator 10 upon the advancement of the tape by feed drum 40 of the perforator.

The end of channel-shaped member 47 opposite the end carrying depending post 48 is turned vertically to form portion 52. Portion 52 has a vertically aligned series of holes, and has secured to it a hardened steel guide block 53 drilled to correspond to the holes in portion 52 and positioned thereon such that its apertures are in alignment with the holes in portion 52. One side of guide block 53 is recessed as shown in Fig. 4 to form a guide-way for tape 28 as it leaves the guide-way formed in the die block 35 and the guide plate associated therewith. Supported in each of the apertures of guide block 53 is a rod 54. Tape 28 having five code perforations, five rods 54 are provided, and each has its end of reduced diameter to facilitate sensing the tape perforations. The ends of rods 54 opposite the ends supported in guide block 53 carry a segment 55 of insulating material which engages, as more clearly shown in Fig. 4, the longer spring 56 of a pair of contact springs 57, there being a pair of springs 57 individual to each rod 54. As will be described later, the position of the rods 54 determines whether the contacts 57 will be opened or closed.

Each of the rods 54 has an enlarged collar 58 and is threaded through an aperture in a plate 59 of insulating material. Plate 59 is secured to armature 60 of an electromagnet 61. Upon the energization of electromagnet 61, armature 60 is attracted against the action of retractile spring 62 which has one end secured to armature 60 and the other end to a spring post 63, plate 59 engages collar 58 on each of the rods 54 and withdraws the rods 54 to free the ends thereof from the perforations in tape 28, and thus allow its advancement.

The advancement of the tape 28 through sensing head 46 is accomplished by the step-by-step rotation of a drum 65 on the periphery of which are formed a plurality of pins 66 arranged to engage the feed hole perforations in tape 28. Drum 65 is supported on a shaft 67 journaled in plate 41. The lower end of drum 65 has a series of ratchet teeth 68 engaged by the free end of a spring-pressed holding pawl 69 and a stepping pawl 70 formed on the end of a lever 71 having its opposite end secured to one arm of a bell crank lever 72, the opposite arm of which is

secured to a plunger 73 of a dash-pot mechanism 74. A spring 75 has one end secured to plate 47 and the other end to lever 71 for holding pawl 70 in contact with the teeth of ratchet 68. An electromagnet 77 is provided with an armature 76 pivoted at 64, and the armature is articulated to the lever 71 at 85. Consequently, when electromagnet 77 is energized, its armature 76 will be attracted against the action of a retractile spring 51 connected thereto for causing pawl 70 formed on lever 71 to cooperate with a tooth on ratchet 68 and rotate drum 65 a distance corresponding to the space of one tooth. When electromagnet 77 is deenergized, the retractile spring 51 on its armature 76 causes lever 71 to return to its normal position to engage the next succeeding tooth of ratchet 68. Thus, when electromagnet 77 is again energized, ratchet 68 and drum 65 will be rotated a distance corresponding to the distance between teeth on ratchet 68. Of course, the rotation of drum 65 causes the corresponding advancement of tape 28.

Cooperating with pins 66 on drum 65 and secured on a post 78 secured to member 47 is a finger 79 which is spring urged to hold the tape 28 firmly in contact with drum 65. Also cooperating with drum 65 and secured to plate 41 is a tape guide 80 formed to direct the path of the tape advanced as a result of the step-by-step rotation of drum 65.

Secured to plate 47 is a bracket 81, the upper end of which carries a rod 82 which has its other end secured to portion 52. Rod 82 acts to hold more securely the parts constituting the tape or record reader 11.

At the lower end of bracket 81 there are supported the plurality of pairs of contact springs 57. A pair of contact springs 57 is individual to each of the rods 54 and has one of its springs longer than the other so as to be engaged by the insulated segment 55 of its associated rod 54.

There is also supported by bracket 81 an additional pair of contacts 83 arranged to be operated by an insulated plunger 84 carried by member 59 secured to armature 60 of the electromagnet 61.

An L-shaped arm 86 is carried by plate 47 and has a disc of insulating material arranged to close a pair of contact springs 87 secured to the depending portion 112 of the transmitter mounting plate 45. The function of contacts 87 will appear from the description which is to follow.

Referring now to Fig. 4, one contact of each of the pair of contacts 57 is connected to a segment of a distributor 88 which includes an outer segmented ring 89, an inner continuous ring 90, and a brush arm 91. Continuous ring 90 is connected to a signaling circuit or line 92 over which signal impulses in accordance with the transverse rows of perforations appearing in tape 28 are to be transmitted through the action of record reader 11. Brush arm 91 carries brushes which bridge successively the segments of outer ring 89 with continuous ring 90, and is secured to a shaft 93 driven from a motor (not shown) through a friction clutch (also not shown). Also secured to shaft 93 on which brush arm 91 is mounted is the arm 94 referred to as a stop arm. Stop arm 94 is adapted to engage the hook end of a bell crank lever 95 operated by an electromagnet 96 and retractile spring 97. Also mounted on shaft 93 is a cam 98 which controls at a predetermined point in the cycle of rotation of shaft 93 the closure of a pair of contacts 99.

Assuming that the keylevers 14 are being operated through the depression of keys 15, tape 28 will be perforated by the action of punches 19 and 21 to form transverse rows of perforations representing the different characters or signals to be transmitted over line conductor or signaling circuit 92. The tape 28 perforated as a result of the operation of punches 21 passes from the die block 35 of the perforator directly to the sensing head 46 of the record reader 11 and in contact with drum 65, the feed pins 66 of which engage the feed holes of tape 28 formed by the operation of feed punch 19.

If it is desired to delay the transmission of signal impulses representing the transverse rows of perforations in tape 28, switch 100, which is included in the energizing circuit of electromagnet 96, is closed, thus preventing the deenergization of electromagnet 96 when contacts 87, which are also included in the energizing circuit of electromagnet 96 are opened upon the initial movement of member 47. Consequently, bell crank lever 95 remains in engagement with arm 94 and brush arm 91 is held against rotation. The continued operation of keylever 14 will perforate tape 28 and force sensing head 46 away from the die block 35 with the assistance of spring 50. The movement of sensing head 46 continues until its movement is arrested due to its engagement with stop 101 secured to the upper surface of base 12. When stop 101 is engaged, as disclosed in Fig. 5, tape 28 will form a loop between the sensing head 46 and the exit of the die block 35 of perforator 10. If switch 100 is now opened, electromagnet 96 becomes deenergized, for contacts 87 were opened when L-shaped member 86 moved free of such contacts due to the movement of plate 47. As a matter of fact, L-shaped member 86 allows contacts 87 to open on the first movement of plate 47 from contact with die block 35. When electromagnet 96 becomes deenergized, spring 97 moves bell crank 95 out of engagement with stop arm 94, thus releasing for rotation brush arm 93 and cam 98 through shaft 93, which, as previously described, is driven from a continuously rotating motor through a friction clutch.

As brush 91 passes successively over the segments 1-5 inclusive of the outer ring 89, such segments will be bridged with continuous ring 90 and impulses depending upon whether contact springs 57 are opened or closed will be transmitted to line conductor 92. The position of contact springs 57 will be determined by the transverse row of perforations in tape 28, for as the tape 28 passes through sensing head 46, the rods 54 are moved or remain in their normal position depending upon whether a perforation appearing in tape 28 is in alignment therewith. However, prior to the transmission of the signal impulses representing characters appearing in the form of perforations in tape 28, the brush arm engages a segment 102 of segmented ring 89 for transmitting to the line a start impulse for initiating the operation of the receiving printer connected to such line 92. During the period the start impulse is being transmitted, cam 98 is effective to close contacts 99. Upon the closure of contacts 99, an energizing circuit is established for electromagnet 61, which in energizing attracts its armature 60 and moves member 59 to withdraw rods 54 through cooperation with the collar 58 formed on each of the rods 54 from engagement with the perforated tape 28 and thus permit the advancement of the

tape 28 upon the rotation of drum 65. Electromagnet 77 is normally short-circuited through contacts 83 controlled by plunger 84 carried by member 59 secured to armature 60 of electromagnet 61. Thus, notwithstanding the fact that contacts 99 are closed, electromagnet 77 is not energized until electromagnet 61 is completely energized and plunger 84 is moved sufficiently to open contacts 83. The opening of contacts 83 removes the short circuit from the winding of electromagnet 77 and allows its energization over a circuit extending from the positive pole of battery 103, closed contacts 99, conductor 104, windings of electromagnets 61 and 77, in series, conductor 105 and resistance 106 to the opposite pole of battery 103. Electromagnet 77 on being energized moves lever 71 and rotates through the cooperation of pawl 70 with ratchet 68 drum 65 for advancing tape 28 to bring the next transverse row of perforations in alignment with the ends of rods 54.

When cam 98 has rotated a predetermined distance, contacts 99 are again opened, and electromagnets 61 and 77 are deenergized. The deenergization of electromagnet 61 withdraws member 59 from engagement with the collar formed on each of rods 54 and allows the spring tension of the contact spring of the pair of contact springs 57 in engagement therewith to move its associated rod 54, which thus senses the presence or the absence of a perforation. If a rod 54 senses a perforation, it will move sufficiently to close its associated contacts 57. However, if the rod senses the absence of a perforation, then the contacts 57 are held open. Consequently, when the brush arm 91 passes over the segments of the outer ring 89 numbered 1-5 inclusive, impulses will be transmitted to line conductor 92 in accordance with the setting of contact springs 57 as determined by the position of rods 54. When brush arm 91 has completed its cycle of rotation, it engages segment 107 of the outer ring 89 and transmits to line conductor 92 a stop impulse which effects a corresponding control on the receiving printing telegraph apparatus connected thereto.

If the perforator 10 has continued to be operated at a high speed, there will be no material reduction in the size of the loop in the tape 28 as shown in Fig. 5. However, if the perforator is not operated at a speed higher than the speed of operation of brush arm 91 of distributor 88, then the size of the loop in the tape 28 will be decreased, even to the point of exhausting the loop of tape, in which case the portion of the tape between the sensing head 46 and the die block 45 of the perforator becomes taut. If there is a cessation in the operation of the perforator, the record reader 11 will continue to sense the transverse rows of perforations in tape 28.

Inasmuch as the feed drum 40 of the perforator is not being operated to emit additional tape, and since the feed drum 65 of the record reader 11 continues its step-by-step rotation upon each energization of electromagnet 77, the sensing head 46 will approach the die block 35. Such approach will continue until the sensing head 46 has engaged the die block 35 and has sensed the last transverse row of perforations in tape 28. When such a condition is established, L-shaped lever 86 brings the insulating disc into contact with contact springs 87 which are thereupon closed and cause the energization of electromagnet 96. When electromagnet 96 is energized, bell crank lever 95 is rotated to bring the hook por-

tion thereof in alignment with stop arm 84 carried by shaft 83 on which brush arm 91 is mounted. Stop arm 84 engages the hook portion of bell crank lever 85 and thus arrests brush arm 91 in its position in engagement with stop segment 107 of distributor 88.

If the perforator 10 is now operated, and provided switch 100 is open, plate 47 will be moved in the direction of the arrow shown in Fig. 1 10 a distance equal to the area occupied by one transverse row of perforations in tape 28, which will be sufficient to move L-shaped member 86 free of contact springs 87, whereupon electromagnet 96 will be deenergized and shaft 83 will be released for rotation. Brush arm 91 and cam 93 will then rotate to achieve their respective functions as previously described. If the perforator is operated at the same speed as the speed 15 of operation of distributor 88, sensing head 46 20 of record reader 11 will not be rotated about post 48. However, if the perforator is operated at a speed higher than the speed of operation of distributor 88, plate 47 will be moved about its pivot 48 until it contacts with stop 101, when 25 its movement will be arrested and a loop will be formed in tape 28 as indicated in Fig. 5.

Although the invention has been disclosed and described as applied to particular apparatus, it is of course understood that many departures 30 and modifications may be made without departing from the spirit and scope of the present invention.

What is claimed is:

1. Telegraph apparatus including mechanism 35 for applying permanent indicia on a record strip representing intelligence characters, mechanism for sensing the indicia on said strip, means for effecting relative movement between said mechanisms, and means effective during said relative 40 movement for causing the transmission of electrical impulses in accordance with the indicia on said strip.

2. In combination with apparatus for applying an unlimited number of permanent indicia on 45 a record strip, apparatus for sensing the indicia including a plurality of sensing fingers cooperating with the indicia, means responsive to said sensing fingers to transmit signal impulses identified with said indicia, and means for advancing 50 said record strip to bring successive indicia in alignment with said sensing fingers and for advancing said sensing fingers along said strip to a point immediately adjacent the point of application of said indicia upon a predetermined 55 condition of said strip.

3. A telegraph transmitter comprising a plurality of members for sensing indicia on a record strip, a movable frame supporting said members, a circuit controller carried by said frame and responsive to the operation of said members, and means for causing the movement of said frame under predetermined conditions of said strip. 60

4. In combination with apparatus for recording 65 transverse rows of perforations in a record strip representing intelligence characters, apparatus for transmitting signal impulses identified with said perforations comprising sensing means including a plurality of elements for sensing the 70 perforations in said strip, means for transmitting signal impulses in accordance with the setting of said elements, and means for causing a relative movement between said sensing means and said recording apparatus when the speed of operation of said recording apparatus bears a pre- 75

determined relationship to the rate signal impulses are transmitted by said transmitting means.

5. In combination with apparatus for recording transverse rows of perforations in a record strip representing intelligence characters, apparatus 10 for transmitting signal impulses identified with said perforations comprising sensing means including a plurality of elements for sensing the perforations in said strip, means for transmitting signal impulses in accordance with the setting of said elements, means for causing a relative movement between said sensing means and said recording apparatus when the speed of operation of said recording apparatus bears a pre-determined relationship to the rate signal impulses 15 are transmitted by said transmitting means, and means for effecting the advancement of said strip into cooperative relation with said sensing elements.

6. In combination with a strip perforator in- 20 cluding code punches and a feed hole punch, means for controlling the effectiveness of said code punches, means for operating said code punches in accordance with the operation of said means and said feed hole punch to perforate a 25 strip with transverse rows of perforations and feed said strip, apparatus for sensing the code perforations in the strip comprising a plurality of sensing fingers movable longitudinally of the strip, contacts controlled by the positions of said 30 fingers for determining the character of the signal impulses to be transmitted, and means co-operating with the feed holes in said strip for moving said sensing fingers along the strip to a point to sense the last row of perforations 35 therein.

7. In combination with a strip perforator in- 40 cluding code punches and a feed hole punch, means for controlling the effectiveness of said code punches, means for operating said code punches in accordance with the operation of said means and said feed hole punch to perforate a strip with transverse rows of perforations and for feeding said strip, apparatus for sensing the code perforations in the strip comprising a plu- 45 rality of sensing fingers movable along said strip, contacts controlled by the positions of said fingers for determining the character of the signal impulses to be transmitted, and means operated in timed relation to the transmission of signaling 50 impulses for advancing said strip through said sensing apparatus and for moving said sensing fingers along said strip when a predetermined number of code perforations appear in said strip.

8. In combination with a perforator for applying code perforations and feed perforations in a strip, means for sensing the code perforations in said strip including a plurality of sensing fingers capable of being moved in a direction of the length of said strip, one for each of the code 60 perforations, means controlled by said fingers for determining the character of signal impulses transmitted, and means for moving said fingers along said strip when a predetermined number of code perforations appear therein. 65

9. In combination with a perforator for applying code perforations and feed perforations in a strip, means for sensing the code perforations in said strip including a plurality of sensing fingers, one for each of the code perforations, means controlled by said fingers for determining the character of signal impulses transmitted, means for moving said fingers along said strip when a pre-determined number of code perforations appear 70 therein, and means for arresting the movement 75

of said fingers in their movement along the strip.

10. In combination with a perforator for applying code perforations and feed perforations in a strip, means for sensing the code perforations in said strip including a plurality of sensing fingers, one for each of the code perforations, means controlled by said fingers for determining the character of signal impulses transmitted, 10 means for moving said fingers along said strip when a predetermined number of code perforations appear therein, and means for arresting the movement of said fingers in their movement along the strip and for causing a cessation in 15 the transmission of the signaling impulses when the last code perforations have been sensed and the signaling impulses therefor have been transmitted.

11. In combination with a perforator for applying code perforations and feed perforations in a strip, means for sensing the code perforations in said strip including a plurality of sensing fingers movable longitudinally of the strip, one for each of the code perforations, means 25 controlled by said fingers for determining the character of signal impulses transmitted, and means cooperating with said feed perforations in said strip for moving said sensing fingers along said strip to sense the code perforations therein.

30 12. In combination with a perforator for applying code perforations and feed perforations in a strip including strip feeding means cooperating with said feed perforations to advance the strip, means for sensing the code perforations 35 in the strip normally abutting said perforator comprising a plurality of sensing fingers movable out of engagement with said perforator directly as a result of the operation of the strip feeding means, and means controlled by said sensing fingers for determining the character of the signal 40 impulses transmitted.

13. In combination with a perforator for applying code perforations and feed perforations in a strip, means for sensing the code perforations in said strip, including a sensing head 45 mounted for pivotal movement, a plurality of sensing fingers carried by said head for sensing the code perforations in said strip, and means cooperating with the feed perforations in said strip for moving said sensing head about its pivot to align the sensing fingers with the last row of 50 code perforations in said strip.

14. In combination with a perforator for applying code perforations and feed perforations in a strip, means for sensing the code perforations in said strip including a plurality of sensing fingers movable longitudinally of said strip, one for each of the code perforations, means 55 controlled by said fingers for determining the character of signal impulses, a rotary distributor including a plurality of contacts cooperating with said last mentioned means for transmitting the signal impulses determined by said means, and means controlled by said distributor for 60 causing the advancement of said sensing fingers along said strip in a direction opposite to the direction in which said strip is directed from said perforator.

15. In combination with a perforator for applying code perforations and feed perforations in a strip, means for sensing the code perforations in said strip including a plurality of sensing fingers, one for each of the code perforations, means controlled by said fingers for determining the character of signaling impulses, 75

a distributor cooperating with said last mentioned means for transmitting the signal impulses determined thereby, means for normally holding said distributor against rotation, and means controlled by the initial advancement of 80 the strip from said perforator for freeing said distributor for rotation.

16. In combination with apparatus for applying indicia on a strip, apparatus for sensing the indicia including a sensing head through which said strip from said applying apparatus is threaded, a plurality of indicia-sensing elements carried by said sensing head, means operated by said sensing elements for determining the character of signal impulses representing said 15 indicia to be transmitted, and means on said sensing head for advancing said threaded strip to bring successive indicia in alignment with said sensing elements and for moving said sensing head along said strip to sense the last recorded 20 indicia.

17. In combination with apparatus for applying indicia on a strip, apparatus for sensing the indicia including a sensing head through which said strip from said applying apparatus is threaded, a plurality of indicia-sensing elements carried by said sensing head, means operated by said sensing elements for determining the character of signal impulses representing said indicia to be transmitted, means on said sensing 30 head for advancing said threaded strip to bring successive indicia in alignment with said sensing elements and for moving said sensing head along said strip to sense the last recorded indicia, and means effective when said sensing head has sensed the last indicia for discontinuing the 35 transmission of signal impulses.

18. In combination with a perforator for applying code perforations and feed perforations in a strip including means responsive to each application of code perforations for advancing the strip, means for sensing the code perforations in said strip comprising a pivoted frame, a sensing head through which said strip is threaded mounted on said frame, a plurality of sensing 45 fingers carried by said sensing head and arranged to sense the code perforations in said strip, means controlled by said sensing fingers in accordance with the code perforations in said strip for determining the character of signal impulses to be transmitted, means for transmitting successively the signaling impulses, and means carried by said frame and controlled by said distributor for alternately withdrawing said sensing fingers from cooperation with said strip 50 and for advancing the strip through said sensing head.

19. In combination with recording mechanism for applying an unlimited number of indicia on a record strip, mechanism for sensing the indicia, including means responsive to the character of the indicia, one of said mechanisms being stationarily mounted and the other movably mounted, and means acting solely through cooperation with said strip for causing relative movement between the respective mechanisms. 60

20. A telegraph instrument comprising a plurality of members for sensing indicia on a record strip, a frame supporting said members movable about a fixed point in one direction until a predetermined number of indicia appear in said strip and in the opposite direction when the number of indicia is below a certain number, a circuit controller responsive to said members, means controlled by the circuit controller for 70 75

transmitting impulses representative of the indicia, and means for effecting the recited movements of said frame.

21. A telegraph instrument including recording mechanism for applying indicia on a record strip, a mechanism movable relatively to said recording mechanism for sensing the indicia on said strip, means responsive to said sensing mechanism for transmitting current impulses indicative of the sensed indicia, and means in said recording mechanism for advancing said strip and, through the advancement of said strip, the sensing mechanism.

22. A telegraph instrument comprising mechanism for applying an unlimited number of indicia on a record strip, mechanism for sensing the indicia, means for movably supporting one of said mechanisms, and means acting solely through cooperation with said strip for causing relative movement between said mechanisms.

23. A telegraph instrument comprising mechanism for applying an unlimited number of permanent indicia on a record strip, mechanism for sensing the indicia, means for movably supporting one of said mechanisms, and means in each of said mechanisms for effecting relative movement between said strip and the associated mechanism, each of said means operable under certain conditions for causing relative movement between said mechanisms.

24. A telegraph instrument comprising mechanism for applying an unlimited number of permanent indicia on a record strip, mechanism for sensing the indicia, means for movably supporting one of said mechanisms, and means in each of said mechanisms for effecting intermittent relative movement between said strip and the associated mechanism, each of said means operable under certain conditions for causing relative movement between said mechanisms. 10

25. A telegraph instrument comprising mechanism for applying an unlimited number of permanent indicia on a record strip, mechanism for sensing the indicia, and means in each of said mechanisms for effecting relative movement between said strip and the associated mechanism, the means in one of said mechanisms operable under certain conditions for causing movement of its associated mechanism. 15

26. A telegraph instrument comprising mechanism for applying an unlimited number of permanent indicia on a record strip, mechanism for sensing the indicia, and means in each of said mechanisms for effecting relative movement between said strip and the associated mechanism, the means in one of said mechanisms operable under certain conditions for causing movement of the other mechanism. 20 25
